UNITED STATES PATENT OFFICE.

TOSHIICHI ARIMITSU, OF YOKOHAMA, JAPAN, ASSIGNOR TO NIPPON YUSEN CO., LTD., OF TOKYO, JAPAN.

AZIMUTH RULER.

Application filed March 31, 1919. Serial No. 286,403.

To all whom it may concern:

Be it known that TOSHIICHI ARIMITSU, subject of the Emperor of Japan, residing at No. 368 Izumitanito, Kitakatamachi, city of Yokohama, Japan, has invented certain new and useful Improvements in Azimuth Rulers, of which the following is a specification.

This invention relates to apparatus for 10 use in solving nautical problems or plane and spherical trigonometry, mechanically and without the use of logarithmic calculations.

The apparatus according to the present 15 invention consists in the provision of a NE arm and a NW arm arranged perpendicular to one another, an arc having its centre at the point of intersection of the inside edges of the said arms and having a scale on its 20 outer edge (graduated 90 degrees), and a scale on the edge of the NE arm having a graduation equal to (OS) the radius of the arc as unit length.

The object of this invention is intended 25 not only to solve mechanically the problems in plane and spherical trigonometry with ease and accuracy, without the use of logarithmic calculations or tables, but it is specially valuable when applied to astronomical 30 navigation, by which the deviation of the compass, alterations in the course of a vessel, or the azimuth of the heavenly body are easily solved.

In the accompanying drawings:

Fig. 1 shows a plan view of this invention.

Figs. 2 to 7 show the application of this invention.

This invention consists of three parts, a 40 NE arm (a), a NW arm (b) and an arc (c), wherein the two arms NE and NW are perpendiculars and the arc is fitted so as to have its centre O at the point of intersection of the inside edges of the arms.

The standard size is 18 inches for the NE 45 arm, 8 inches for the NW arm, and 6 inches in radius for the arm for all practical purposes. It is to be understood however, that these sizes can be varied, if desired.

The special feature of this invention is 50 the combination of the angular graduation on the arc and the scale on the NE arm which graduation is made with the radius of the arc as unit of length, the point of unit.

If the instrument is made of transparent substances, the scale and the graduation are arranged under the surface of the instrument, for reducing the parallax of the reading to a minimum. 60

If however the instrument is made of metallic substances, the graduations are arranged on the surface, and the method of minimizing the parallax of the reading is to bevel a part of the graduation to a knife 65 edge.

The method of using the apparatus will now be explained with reference to Figures 2 to 7.

In these figures M and L represent perpendiculars on the Mercator's chart, L being the "parallel of latitude" and M the "line of meridian." 70

In order to commence calculations the apparatus as illustrated in Figure 2 is placed 75 on the chart, so that the "parallel of latitude" L will make tangent with the arc and the centre of the arc O will coincide with the line of meridian M.

This relative position of the apparatus 80 with the cross lines M and L is called "tangent form" which is one of two "fundamental forms" from which nautical calculations are started.

These two "fundamental forms" are 85 known as "tangent form" and "sine form," the latter being classified into "No. 1 sine form" and "No. 2 sine form."

The cross lines M and L with the apparatus at the position known as "tangent form" 90 as shown in Figure 2 will make two right angled triangles, the several sides of which represent the trigonometrical functions of tan (tangent) cot (cotangent), sec (secant), cosec (cosecant). 95

According to Figure 3 the apparatus is placed on the chart so that the point S coincides with the line of latitude L and the centre of the arc O with the "line of meridian" M. 100

This relative position of the apparatus with the lines M and L describes the other "fundamental form" from which calculations are started and which is known by the name of "sine form." 105

The cross lines M and L at this position form a right angled triangle and each side will represent the trigonometrical function of sine and cosine as shown in Figure 3.

In order to use the apparatus for solving 110

problems in nautical astronomy such as finding the azimuth of a heavenly body and thence the deviation of the compass, there are several kinds of motions which are 5 started from one of the above mentioned "fundamental forms." A motion which is started from "tangent form" is called "tan motion" and relates to a motion of the apparatus in which the centre of the arc O slides 10 along the line of meridian M, keeping the length of the tangent a fixed quantity, as shown in Figure 5.

A motion which is started from "sine form" is called "sine motion" and relates to 15 a motion of the apparatus in which the centre of the arc O slides along the line M, keeping the length of the sine a constant quantity as shown in Figure 6.

Slide motion is one wherein a fixed length 20 is taken on the scale such as O R, O being the centre of the arc sliding on the line M and R a point on the NE arm sliding along the line L. For every position, therefore, 25 of the apparatus with respect to the cross lines M and L the length O R will be constant, that is to say OR=O, R.

The motion, in No. 2 "sine form" is turned into a "turning motion" and is called "sine turning motion." In this motion the apparatus is placed in position with relation to the cross lines as shown in Figure 4, the centre of the arc O coinciding with the line M. The apparatus is turned about the point O keeping the length M a constant quantity 35 as shown in Figure 7.

An example will now be given showing the method of solving nautical formula by the use of this device.

Example 1.

$$\tan L \cdot \cot H = A.$$

where

L=latitude.

H=hour angle.

40 Place the instrument in the position shown in dotted lines in Fig. 5, placing the junction of the two arms on the meridian line M and arranging the arm *a* so that the graduation 45 on that arm corresponding to the latitude given is intersected by the parallel L.

Mark the point of this intersection and then move the instrument in such manner that the intersection of the two arms follows

upward along the meridian line M, while 55 the arm *a* is constantly kept on the marked point on the parallel of latitude. Continue this motion until the meridian line M intersects the hour angle as read on the arc *c*. Then the distance, as measured by the scale 60 on the arm *a*, from the point of intersection of the two arms with the meridian line M to the point of intersection of the meridian and parallel of latitude L, will equal A.

Example 2.

$$\sin H \cdot \cosec z \cdot \cos d = \sin Az.$$

where

H=hour angle.

Z=zenith distance.

d=declination.

Az=azimuth.

70 Place the instrument, as shown in Fig. 3, so that the intersection of the two arms coincides with the meridian line M, the intersection of the end of the arc *c* with the arm *a* coincides with the parallel of latitude L, and the meridian line M cuts the hour angle given as read on the arc *c*. Now move the 75 instrument through the sine motion until the meridian line intersects the arc *c* on the zenith distance, and read on the scale of the arm *a* the distance between the intersection of the arms and the parallel of latitude 80 calling this *m*. With this value as a constant, rotate the instrument on the center of the arc *c* until the position previously described as No. 2 sine form has been obtained. Then the azimuth may be read directly on 85 the arc *c*.

I claim—

90 Apparatus for use in solving nautical problems or plane and spherical trigonometry comprising arms arranged perpendicular to one another, an arc having its centre at the point of intersection of the inside edges of the said arms and having a scale 95 on its outer edge graduated 90 degrees and a scale on the edge of one arm having 100 a graduation equal to the radius of the arc as unit of length.

In testimony whereof he affixes his signature in the presence of two witnesses.

TOSHIICHI ARIMITSU. [L.S.]
